F. W. GRADY

PIPE ELEVATOR

Filed Jan. 20, 1925.

Inventor

E.W. Grady

By *Chaswells*

UNITED STATES PATENT OFFICE.

FRANK W. GRADY, OF LOMITA, CALIFORNIA.

PIPE ELEVATOR.

Application filed January 20, 1925, Serial No. 3,612.

To all whom it may concern:

Be it known that I, FRANK W. GRADY, a subject of Great Britain, residing at Lomita, in the county of Los Angeles and State of California, have invented a new and useful

5 Pipe Elevator, of which the following is a specification.

This invention has reference to devices especially designed for use in lifting well 10 pipes or tubing, the primary object of the invention being to provide a device of this character which may be attached to pipes, tubings, casings or sucker rods, in the usual and well known manner and swung into engagement with the pipe or tubing to be 15 lifted, the jaws forming a part of the device automatically gripping the pipe or tubing.

Another object of the invention is to provide a device of this character whereby the 20 jaws will be automatically moved around the pipe or tubing upon the engagement of the pipe with the inner ends of the jaws, which lock automatically with latching devices.

25 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

35 Referring to the drawing:

Figure 1 is a plan view of an elevator constructed in accordance with the invention, the jaws thereof being shown in their 40 open positions.

Figure 2 is a plan view of the elevator, the jaws being shown in their closed positions.

45 Figure 3 is a sectional view through the jaw supporting shafts.

Figure 4 is a fragmental plan view of a modified form of the locking device.

50 Referring to the drawing in detail, the body portion of the device is indicated by the reference character 5 and is preferably semi-circular in formation, the same having laterally extended bearing members 6 that are disposed within the links 7, which are supported in the usual and well known manner.

At the ends of the body portion 5 are spaced bearing members 8 in which the shafts 9 are positioned, which shafts provide supports for the jaws 10. The shafts 9 are held against movement within the bearing members 8 by means of the pins 11 that are shown as positioned in registering notches formed in the bearings and shafts 9. Each of the shafts 9 is provided with a lug 12 that supports a pin 15 that acts as a support for one end of the coiled spring 14 associated therewith, the opposite end of the coiled spring being secured to the jaw 10 associated therewith at a point adjacent to the outer end thereof as by means of the 70 bolt 15'.

Thus it will be seen that due to this structure, when the jaws are moved to their closed positions, the springs will be placed under lateral tension to the end that when 75 the locking means to be hereinafter more fully described, is released, the springs 14 will act to urge the jaws to their open positions as shown by Figure 1 of the drawing.

The jaws include inwardly extended end 80 pieces 16 that are provided with cut out portions 17 defining shoulders to be engaged by the latch members 18 that are pivotally supported within the body portion at 19.

85 Each latch member is provided with an inwardly extended end portion 20 that is apertured to receive the pin 21 associated therewith, the pins 21 being also carried by means of the head 22 formed on one end of the rod 23, the opposite end of the rod supporting the finger piece 24. Mounted on the rod 23 is a coiled spring 25 that bears against the head, at one of its ends, the opposite end of the spring resting on the 90 shoulder 26 so that as the finger piece 24 is moved in one direction, the spring 25 will be placed under compression, and the latch members 18 moved to disengage the shoulders of the end pieces 16 of the jaws. When 95 the finger piece 24 is released, it will be obvious the coiled spring 25 will return the latch members 18 to their normal positions.

The finger piece 24 operates within the member 27 that acts as a hand-hold to be 100 gripped by the operator when it is desired to release the latch members 18.

In the form of the invention as illustrated by Figure 4, the body portion of the elevator is indicated at 30 and supports swivel 110

jaws that are provided with end pieces 31, which end pieces are provided with curved portions 32 that permit them to ride over the locking member 33 which is in the form 5 of a block that moves between the adjacent end pieces 31 in a manner as shown by Figure 4 of the drawing to the end that outward movement of the jaws is absolutely restricted while the block is in such locking 10 position.

A rod indicated at 34 operates through the bearing member 35 and carries the handle 36, there being provided a coiled spring 37 surrounding the rod to be compressed 15 when the handle 36 is moved to disengage the block 33 from the end pieces so that when the block 33 has been moved to disengage the end pieces and the jaws are moved to their open positions, the block will 20 be forced inwardly to lie in the path of travel of the end pieces 31 of the jaws.

From the foregoing it will be obvious that by moving the body portion into engagement with a pipe to be lifted when the jaws 25 are in a position as illustrated by Figure 1 of the drawing, the end pieces 16 will engage the pipe to the end that the jaws will be moved to their closed positions embracing a portion of the pipe.

With the jaws in this position, it will be seen that the latch members 18 will auto-

matically move to hold the jaws in their locking positions.

I claim:

1. A pipe lifter including a body portion, 35 jaws pivotally supported on the body portion and having inwardly extended end portions formed with shoulders, a pair of pivoted latch members adapted to engage the shoulders to lock the jaws in their active 40 positions, means for moving the latch members simultaneously to release the jaws, and spring members for normally urging the jaws outwardly.

2. A pipe lifter including a body portion, 45 a pair of pivoted jaws carried by the body portion, shafts on which the jaws are mounted, lugs extending laterally from the shafts, coiled springs having their inner ends mounted on the lugs, the outer ends of 50 said spring members being connected with the jaws, said spring members being normally arranged at oblique angles with respect to the inner surfaces of the jaws to normally urge the jaws to their inactive positions, and latch members for locking the jaws in their active positions.

In testimony that I claim the foregoing as my own, I have hereto affixed my signature.

FRANK W. GRADY.
